[57] CLAIM

The ornamental design for a tire, as shown and de-
scribed.

DESCRIPTION

FIG. 1 is a perspective view of a tire showing one em-
bodiment of my new design, it being understood that
the tread pattern is substantially the same throughout
the circumference of the tire, as shown schematically by
solid lines, the opposite side being substantially the same
as that illustrated;

FIG. 2 is an enlarged, fragmentary plan view of the
embodiment of FIG. 1;

FIG. 3 is a perspective view of a tire showing another
embodiment of my new design, it being understood that
the tread pattern is substantially the same throughout
the circumference of the tire, as shown schematically by
solid lines, the opposite side being substantially the same
as that illustrated; and,

FIG. 4 is an enlarged, fragmentary plan view of the
embodiment of FIG. 3.
